UNITED STATES PATENT OFFICE.

CHARLES U. CARPENTER, OF DAYTON, OHIO.

SHEET-METAL STRUCTURE.

1,373,865.

Specification of Letters Patent. Patented Apr. 5, 1921.

Application filed July 10, 1919. Serial No. 309,815.

To all whom it may concern:

Be it known that I, CHARLES U. CARPENTER, a citizen of the United States, residing at Dayton, in the county of Montgomery and State of Ohio, have invented certain new and useful Improvements in Sheet-Metal Structures, of which the following is a specification.

My invention relates to sheet-metal structures for employment, for instance, in sheet-metal office and household furniture, such as filing and other cabinets, book-cases, desks, heat-resisting safes, refrigerators, and other articles.

My invention relates primarily to means whereby sheet-metal sheets of comparatively large area may be employed in such manner that comparatively thin sheet-metal may be used with the assurance that the sheet will be stiff and resistant and bending and buckling thereof prevented.

It has heretofore been a usual practice to obtain stiffness and rigidity by employment of comparatively heavy sheet-metal, which, due to the increasing cost of material of this character, has been found to be expensive, and in many cases prohibitive by reason of increasing the cost of the article to a greater amount than a reasonable or possible selling price thereof.

It is the object of my invention, therefore, to provide novel means to make the employment of comparatively thin sheet-metal possible, in such manner that sheet-metal of extended area is resistant and inflexible while preserving a smooth outer surface; further, to provide novel strengthening means for the inside of a sheet-metal structure of extended area while maintaining the outer surface thereof a plane surface; further, to provide a novel sheet-metal structure of extended area comprising a thin sheet of metal and reinforcing means fixed to the sheet of metal along said reinforcing means; and, further, to provide a composite sheet-metal structure embracing a sheet of metal of extended area and reinforcing means thereto, one of the elements of the composite structure being provided with novel connecting means whereby to connect adjacent structures.

The invention will be further readily

understood from the following description and claims, and from the drawings, in which latter:

Figure 1 is an inside elevation of the frame of a cabinet, exemplifying my invention, taken in the plane of the line 1—1 of Fig. 3.

Fig. 2 is an inside elevation of the same, taken in the plane of the line 2—2 of Fig. 3.

Fig. 3 is a cross-section of the same, taken in the plane of the line 3—3 of Fig. 1.

Fig. 4 is a perspective view showing the corner arrangement of the present exemplification of my invention, taken in the direction of the arrows 4—4 of Fig. 3, the parts being partly broken away.

Fig. 5 is a perspective view of one of the front corners of my improved device, partly broken away.

Fig. 6 is a perspective detail view of one of the front corners embodied in the present exemplification of my invention, viewed from the outside in the direction of the arrow 6 in Fig. 3, and partly broken away.

Fig. 7 is a plan sectional detail, taken on the line 7—7 of Fig. 5.

Fig. 8 is a perspective view of one of the upper corners of my improved device, showing a top-piece received thereover, the same being partly broken away.

Fig. 9 is a vertical section of the same, taken on the line 9—9 of Fig. 8.

Fig. 10 is a perspective view showing the lower end of one of the upright corner-pieces, having a foot-piece thereover, the same being partly broken away.

Fig. 11 is a cross-section of the same, taken on the line 11—11 of Fig. 10.

Fig. 12 is a detail of a modification, taken in section on a line corresponding to the line 7—7 of Fig. 5; and,

Figs. 13 and 14 are cross-sectional details taken respectively on the lines 13—13 and 14—14 of Fig. 1.

My invention is exemplified as employed in a sheet-metal structure representing the frame of a cabinet, for instance, the frame of an office filing cabinet. The frame is exemplified at 21 as comprising sides 22 and a back 23. The sides and back may, for convenience, be designated as walls. Upright corner-pieces 24 may be employed for con-

necting the walls. Cross-bars 25 are shown as extending across the front of the cabinet, connecting the front corner-pieces, forming openings 26 for receiving suitable drawers 5 on suitable runways in the cabinet, the drawers and runways not being shown as they are not a part of the present invention.

A top-piece 27 may be received over the upper ends of the walls and corner-pieces.

10 Each of the walls is exemplified as comprising a sheet 31 of metal, for instance, sheet steel, the sheet being comparatively thin, of such thinness in fact that it would, if unsupported, flex or bend and yield readily over extended areas to forces applied perpendicular to its side surfaces. This sheet of metal is bent at its margins to form flanges 32, shown as right-angular flanges, which are arranged to lap at the corners, as 15 shown by the laps 33, suitably connected to the adjacent flanges, as by electric spot welds, indicated at 34.

Reinforcing strips 35, 36, are arranged across the inner face of the sheet 31, and 20 are shown as provided with flanges 37, shown as right-angular flanges, bent from the bodies of the strips. These strips are also of comparatively thin sheet metal, for instance sheet steel, similar to the sheet 31.

25 30 The reinforcing strips and the sheet of metal are fixed together, preferably at intervals, lengthwise of the strips, so as to unite the proximate surfaces of said strips and sheet to form the composite wall. This uniting may be accomplished by means of rivets 40, as shown in Fig. 12, but I prefer to unite the same by means of electric spot welding, as indicated by the spot-welds 41, as shown in Figs. 7 and 14. These 35 40 spot-welds are arranged lengthwise of the reinforcing strips. I have found by experiments that electric spot welding has a tendency to weaken the metal surrounding the spot which is welded, so that by first twisting the united parts at the spot-welds, the parts united by the spot welding may be severed or pulled apart by stresses perpendicular to the surface of the material. Such 45 weaknesses are, however, avoided in my improved structure, in which preliminary twisting strains upon the welds are resisted by the arrangement and structure of the parts composing the composite wall, providing a firm union between parts which is not 50 liable to become severed.

I prefer to arrange the angular reinforcing strips obliquely or diagonally across the inner face of the sheet of metal of the structure, providing main reinforcing strips 35 55 extending over a substantial area of the sheet, and auxiliary diagonal reinforcing strips 36, which connect with the main diagonal reinforcing strips. The diagonal reinforcing strips also preferably connect with the marginal flanges 32 of the sheet.

I have shown the connections between the diagonal reinforcing strips as consisting of lips 44, integral with the flanges 37 of one of the diagonal strips, received through slots 45 in the flanges of the mating diagonal strips, the lips being provided with apertures through which pins 47 are received for locking the flanges together. These pins may, if desired, be slightly wedge-form, as shown at 48, and be provided with a head 49 extending from one side thereof. The face of the pin adjacent to the flange lengthwise of which it extends, impinges closely against this flange for wedging the flanges together. 75 80

The outer ends of the flanges of the diagonal strips are extended as lips 51, integral with said flanges, and bent at angles from said diagonal flanges, the lips being preferably perpendicular to the marginal flanges of the sheet. These latter lips extend through slots 52 in the marginal flanges 32, the lips being provided with apertures 53, through which locking pins 54 are received, these locking pins being preferably 85 similar to the locking pins 47, for locking the flanges rigidly together. 90

The locking pins may be of desirable lengths, so as to be received through one or more of the locking lips. Thus locking 95 pins 50 are shown as passing through but one of the locking lips, the locking pins 47 passing through the respective pairs of locking lips extending from the flanges at the respective edges of a single reinforcing 100 strip, and the intermediate locking pins 54 extending through a plurality of adjacent pairs of lips.

The diagonal reinforcing strips, which are interconnected and connected with the 105 marginal flanges of the sheet of metal, and the sheet of metal, have their proximate surfaces fixedly united substantially throughout the lengths of said reinforcing strips, preferably at close intervals, as exemplified by the spot weldings 41, which extend along the length of the reinforcing strips, thereby forming a composite truss-braced sheet, the truss-bracing structure 110 whereof is substantially integral with said 115 sheet.

The corner-pieces, exemplified at 24, may, if desired, be of heavier sheet metal than the composite walls. These corner-pieces are exemplified as upright corner-pieces 120 comprising respectively outer upright walls 57, 58, and inner flanges 60, 61, extending from the latter walls, the latter walls and the flanges being bent at the angles thereof for forming an integral upright corner-piece. The flanges 60, 61, of the rear corner-pieces and the flanges 61 of the front corner-piece are provided with slots 63 which register with the slots 52 in the marginal flanges of the sheet member of the com- 125 130

posite wall, the lips 51 extending through the slots 52 in said marginal flanges and the slots 63 in the said named flanges of said corner-pieces, the locking pins extending 5 through the apertures in said lips at the insides of said corner-pieces for locking said composite walls and said corner-pieces together.

The front cross-bars 25 are shown formed 10 as sheet-metal channels comprising a front web 65 and rearwardly extending flanges 66. The ends of the latter are provided with lips 67, integral with said flanges. The lips 67 extend through slots 68 in the flanges 15 60 of the front corner-pieces, pins 69 being received through apertures 70 in said lips for distancing the front corner-pieces from each other and rigidly connecting the same.

The lips 44, 51, 67, are preferably narrower than the flanges from which they extend, so as to be respectively received 20 through slots 45, 52, 63, and 68, which are narrower than the respective flanges in which they are located, thereby providing 25 shoulders 71, 72, 73, at the ends of the flanges from which the lips extend, against which the flanges in which the respective slots are located are arranged to abut, in order to lock the latter flanges in fixed relation between 30 said shoulders and the respective locking pins.

If it is desired to strengthen the upper or lower portions of the upright corner-pieces, or either of the same, for maintaining the 35 cross-sectional relations of the upright walls and flanges thereof, means may be provided which are received at the inside and outside of said upright walls and flanges of the corner-pieces for relatively positioning the same. For convenience the said walls as 40 well as said flanges may be designated walls.

Thus the top-piece 27 may be provided with depending flanges 75, the front one of which may be provided with a cornice 76. The depending flanges are received about 45 the outer faces of the composite walls and the upright corner-pieces. The upper portion of the top-piece may, at each corner thereof, be provided with a downward bulge 50 77, received inside the lengthwise space in the corner-piece, and with downward bulges 78, 79, forming recesses into which the upper ends of the walls of the corner-piece extend. In other words, the bulges and the 55 downwardly extending flanges form recesses 80 in which the upper ends of the upright walls of the corner-pieces are received for positioning said upright walls with relation to each other.

Foot-pieces 81 may also be provided. Each of the foot-pieces is provided with outer upwardly extending flanges 82 which surround the lower end of the corner-piece over which it is placed, the bottom of the 65 foot-piece being provided with an upward

bulge 83 forming an inside marginal recess 84 around the lower end of the inside of the foot-piece, for receiving the lower ends of the upright walls of the corner-piece so as to prevent relative movement between 70 the same.

I am, by means of my invention, enabled to obtain extreme rigidity while employing comparatively thin sheet metal; further, to obtain an inflexible light sheet-metal structure; further, to assemble the sheet-metal structure in such manner as to be readily put together and taken apart, whereby the same may occupy small space and be economical for carriage, storage and shipment; 80 and, further, to readily and economically form the parts.

Having thus fully described my invention, what I claim as new and desire to secure by Letters Patent, is:

1. A composite sheet-metal wall comprising a comparatively thin sheet of metal of extended area, and reinforcing strips extending in a plurality of directions across the face of said comparatively thin sheet of 90 metal, the major portions of said reinforcing strips distanced from the margins of said comparatively thin sheet of metal, said reinforcing strips rigidly interconnected and rigidly connected with said sheet along 95 said reinforcing strips.

2. A composite sheet-metal wall comprising a comparatively thin sheet of metal having its margin bent into flanges extending integrally therefrom, and reinforcing strips 100 having flanges bent integrally therefrom, and extending diagonally across the face of said comparatively thin sheet of metal, with the face of said comparatively thin sheet of metal and the faces of said reinforcing strips 105 in juxtaposition, the said sheet and reinforcing strips having their proximate surfaces rigidly connected, and connecting means including extensions of said flanges of said reinforcing strips between said marginal flanges and said flanges of said reinforcing strips.

3. In a sheet-metal structure, the combination of a composite sheet-metal wall comprising a sheet of sheet-metal of extended area having a marginal flange integrally bent therefrom, and diagonal sheet-metal reinforcing strips having marginal flanges extending lengthwise thereof integrally bent therefrom, the proximate surfaces of said reinforcing strips and said sheet rigidly connected, and an upright corner-piece provided with an upright wall which coacts with said first-named flange, said first-named flange and said last-named 115 wall provided with registering slots, and said second-named flange provided with lips extending integrally therefrom and through said slots, and means for securing said parts together.

4. In a sheet-metal structure, the combination of a composite sheet-metal wall comprising a sheet of metal of extended area having a marginal flange integral therewith bent therefrom, and diagonal sheet-metal reinforcing strips having marginal flanges extending lengthwise thereof integral therewith and bent therefrom, the proximate surfaces of said reinforcing strips and said sheet rigidly connected, an upright corner-piece provided with upright walls, one of said walls coacting with said first-named flange, said first-named flange and said last-named wall provided with registering slots, said second-named flanges provided with lips integral therewith and extending therefrom and through said slots, means for securing said parts together, and an end-piece provided with positioning means for the respective upright walls of said corner-piece.

5. In a sheet-metal structure, the combination of composite sheet-metal walls respectively comprising a sheet of metal of extended area having marginal flanges integral therewith bent therefrom and diagonal sheet-metal reinforcing strips having marginal flanges extending lengthwise thereof integral therewith, and bent therefrom, the proximate surfaces of said reinforcing strips and said sheet rigidly connected, upright corner-pieces respectively provided with upright walls, the upright walls of said corner-pieces coacting with said first-named flanges, connecting means between said first-named flanges and said last-named walls for rigidly connecting the same, and end means for said respective corner-pieces provided

with positioning means for the respective walls of said corner-pieces.

6. In a sheet-metal structure, the combination of composite sheet-metal walls respectively comprising a sheet of sheet metal of extended area having marginal flanges integral therewith bent therefrom and diagonal sheet-metal reinforcing strips having marginal flanges extending lengthwise thereof integral therewith and bent therefrom, the proximate surfaces of said reinforcing strips and said sheet rigidly connected along the lengths of said reinforcing strips, upright corner-pieces respectively provided with upright walls, the upright walls of said corner-pieces coacting with said first-named flanges, said first-named flanges and said last-named upright walls provided with registering slots and said second-named flanges provided with lips extending integrally therefrom received through said slots, means for securing said parts together, a top-piece provided with positioning parts received at the respective sides of the upper ends of said walls of said corner-pieces, and foot-pieces provided with positioning parts received at the respective sides of the bottoms of said walls of said corner-pieces.

In testimony whereof, I have hereunto signed my name in the presence of two subscribing witnesses.
